COMBINED WALKER AND TRAY FOR A CHILD

Shoichi Itoh, Tokyo, Japan, and Elmer Rocker, Shaker Heights, Ohio, assignors to Century Products, Inc., Cleveland, Ohio

Filed May 4, 1970, Ser. No. 22,808

Term of patent 14 years

Int. Cl. D6—02

U.S. Cl. D15—1

FIG.1

FIG.4

FIG. 1 is a generally perspective view of the combined walker and tray for a child showing our new design;

FIG. 2 is a generally perspective view of the opposite side of the device shown in FIG. 1;

FIG. 3 is a top plan view thereof; and

FIG. 4 is a bottom plan view thereof.

We claim:

The ornamental design for a combined walker and tray for a child, as shown.
